CAM DIAL CONTROL FOR A FERTILIZER SPREADER OR SIMILAR ARTICLE

William Schiebel, East Stroudsburg, Pa.

Application August 5, 1958, Serial No. 52,049

Term of patent 14 years

(Cl. D52—1)

FIG. 1.

FIG. 2.

Figure 1 is a front elevation of a cam dial control for a fertilizer spreader or similar article, showing my new design; and

Fig. 2 is a side elevational view thereof.

The dominant features of the design reside in the full line portions.

I claim:

The ornamental design for a cam dial control for a

fertilizer spreader or similar article, as shown and described.
